UNITED STATES PATENT OFFICE.

ZACHARY TAYLOR RICKARDS, OF PHILADELPHIA, PENNSYLVANIA, AS-SIGNOR TO THE FULTON & WALKER COMPANY, OF SAME PLACE.

DESIGN FOR A WAGON-BODY.

SPECIFICATION forming part of Design No. 22,470, dated May 23, 1893.

Application filed March 14, 1893. Serial No. 465,976. Term of patent 7 years.

To all whom it may concern:

Be it known that I, ZACHARY TAYLOR RICKARDS, a citizen of the United States, residing in the city and county of Philadelphia, in the State of Pennsylvania, have invented and produced a new and original Design for a Delivery-Wagon Body, of which the following is a specification.

The object of my invention is to produce a design for a wagon body intended for the transportation of merchandise, in which shall be combined with graceful outlines, a novel disposition of openings in relation to the side wall space of the wagon body, as a result of which the side of said body shall present a symmetrical and well balanced arrangement of solid and open panels.

Referring to the accompanying illustration which represents my design for a wagon body, it will be observed that the wagon body therein depicted is in the direction of its height divided into three longitudinally extending belts or divisions, designated respectively A, B and C. The upper belt or division, A, is, as shown, of narrow depth, extends from end to end of the carriage body, and is somewhat arciform so that its upper edge is flush with and follows the curvature of the roof which is itself of convex form. The lower belt or division, C, is of a depth several times in excess of that of the division A, extends from end to end of the wagon body, and as to its upper edge follows a curve of the same radius

as that of the lower edge of the belt or division A, but in a correspondingly opposite or reverse direction. The intermediate belt or division, B, is divided longitudinally into three spaces or panels, the upper and lower edges of which respectively conform to the adjacent curved edges of the upper and lower divisions, and the respective end panels of which belt embody or are formed as openings, placed, as stated, at equal distances from the longitudinal center of the wagon body. The belt or division, A, the central panel of the belt or division, B, and the upper portion of the belt or division C, are all represented as having a ground of a common texture or appearance, and as bearing ornamental markings, and they may also bear words which constitute announcements or advertisements. The remaining portion of the wagon body below the line x—x is represented as being divided up by lines of beading or light moldings, both horizontally and vertically disposed.

Having thus described my design, I claim and desire to secure by Letters Patent—

The design for a wagon body, herein shown and described.

In testimony that I claim the foregoing as my invention I have hereunto signed my name this 24th day of February, A. D. 1893.

ZACHARY TAYLOR RICKARDS.

In presence of—

J. BONSALL TAYLOR,
F. NORMAN DIXON.
